UNITED STATES PATENT OFFICE

159,485

CIGARETTE DISPENSER

Daniel N. Hesmer, Sr., Cheektowaga, N. Y.

Application April 21, 1949, Serial No. 2,173

Term of patent 14 years

(Cl. D52—2)

To all whom it may concern:

Be it known that I, Daniel N. Hosmer, Sr., a citizen of the United States, residing at Cheektowaga, in the county of Erie and State of New York, have invented a new, original, and ornamental Design for Cigarette Dispenser, of which the following is a specification, reference being had to the accompanying drawing, forming a part thereof.

Figure 1 is a perspective view of a cigarette dispenser embodying my new design showing the same in its normal position. Figure 2 is a similar view showing the same in a position for dispensing a cigarette. Figure 3 is an end view of the dispenser.

I claim:

The ornamental design for a cigarette dispenser, substantially as shown.

DANIEL N. HOSMER, SR.
